CLAIM

The ornamental design for a check presenter with a view window, as shown and described.

DESCRIPTION

FIG. 1 is a perspective view of the exterior of a check presenter in an open position showing a new design;

FIG. 2 is a perspective view of the interior of the check presenter of FIG. 1 in an open position;

FIG. 3 is a perspective view of the check presenter of FIG. 1 in a closed position; and,

FIG. 4 is a front view of the check presenter of FIG. 1 in a closed position.

The broken line are for environmental purposes only and form no part of the claimed design.
